UNITED STATES PATENT OFFICE

WILLETT C. MAGRUDER, OF LOUISVILLE, KENTUCKY

RAZOR CABINET

Application filed April 23, 1928. Serial No. 272,130.

This invention relates to razor cabinets and it is one of the objects of the invention to produce a razor cabinet comprising a single tile and adapted to be set at a convenient height in the wall of a bath room, thereby providing a suitable support, for such articles as safety razors and blades.

A further object of this invention is to provide a cabinet of the above character and also having an opening extending into the interior of the wall.

This invention will be better understood upon reference to the accompanying drawings, in which like reference characters de-

15 note like parts in each of the several views.

Figure 1 is a face view of the razor cabinet, formed according to my invention.

Figure 2 is a cross section of a fragment of a wall having a razor cabinet according 20 to my invention set therein, the section of the razor cabinet shown in Figure 2 being taken along the line 2—2 of Figure 1.

Figure 3 is a plan view of the form of razor cabinet shown in Figures 1 and 2.

25 The reference numeral 1 indicates the face of the tile razor cabinet. The face of the cabinet is made ordinarily in the same size and shape as the other tiles with which the face of the wall is covered. These other

30 tiles are indicated by the reference numeral 2 and are of well known construction, being made in any suitable shape and sizes. The reference numeral 3 represents an extension projecting from the back of the tile and extending through the plaster or cement 4, which holds the tiles of the wall in place. The plaster is in turn supported by any suitable means, such as the usual steel netting 5. The projection is hollow and defines a recess

35 6, which is of suitable size to contain a safety razor and package of blades, or any other articles for which a convenient receptacle is desired. The lower side, 7, of the receptacle is substantially at right angles to the face 1,

40 so that there will be no tendency for the razor to slip out of the cabinet, but the upper side 8 and also the ends 9 are given a slight taper or draw for convenience in manufacturing.

45 50 The outside of the projection 3 will be slightly tapered toward the back, as shown, for

convenience in manufacturing. The back end 10 of the projection 3 forms a wall to prevent large articles from falling into the interior space 11 of the wall. The end 10, however, is provided with a small slit-like opening 12. This opening is preferably of suitable size to conveniently pass a safety razor blade. By the provision of this opening used razor blades may be conveniently discarded by dropping them into the wall. The small size of the opening prevents larger articles being accidentally dropped into the wall and also avoids the unsightly appearance the larger opening would present.

It will be seen that I have provided a new and useful razor cabinet and that the invention is susceptible of various modifications. I accordingly do not wish to be limited in my protection as set forth in the following claims.

I claim:

1. As an article of manufacture a razor cabinet comprising a wall tile unit adapted to be set in the plaster of the wall and to extend therethrough into a vacant space in the wall, a recess in the face of said unit of suitable size to accommodate a safety razor and a small opening from said recess into the said vacant space.

2. As an article of manufacture, a razor cabinet comprising a body member having a substantially rectangular face and adapted to be set in a wall with the surface substantially flush with the surface of the wall, a recess in said member of suitable size to accommodate a toilet article, and an opening of smaller size than said recess leading from the back of the recess through the back of the body member.

In testimony whereof I have affixed my signature.

WILLETT C. MAGRUDER.
